CLAIM

The ornamental design for a shoe as shown and described.

DESCRIPTION

FIG. 1 is a front perspective view of a shoe showing my new design;
FIG. 2 is a side view thereof; and,

FIG. 3 is a rear perspective view thereof.

The even-length broken lines and the even-length zig-zag broken line represent stitching that forms no part of the claimed design. The uneven-length broken lines within the shaded area represent lacing elements that form no part of the claimed design. The uneven-length broken lines depicting the remainder of the shoe form no part of the claimed design.
